5 Claims. (Cl. 252—161)

This invention is concerned with novel detergents of 15 the alkyl aryl sulfonate-type and particularly with products which exhibit unusually high detergency at low concentrations in hard water. More particularly this invention is concerned with compounds of the formula,

wherein R is an alkyl radical of 2 carbon atoms and R' is a straight chain alkyl radical containing 8 to 9 carbon atoms per molecule and wherein X is a radical selected from the group consisting of sulfonic acid group and water-soluble salts thereof.

Alkyl aryl sulfonates have long been known as detergents. It has been found, however, that sulfonates of one structure possess advantages over alkyl aryl sulfonates of another structure. According to this invention alkyl aryl sulfonates containing a straight chain alkyl group of 11 to 12 carbon atoms in which the benzene nucleus is attached to the third carbon atom of the alkyl chain, are superior to isomeric sulfonates in which the benzene nucleus is attached to other carbon atoms of the alkyl chain. The advantages of the alkyl aryl sulfonates in which the nucleus is attached to the third carbon atom of the alkyl chain lies in their outstanding behavior as water-soluble detergents at very low concentrations. Compounds which are typical of this invention are the mono-sulfonated alkali metal salts of 3-phenyldodecane and 3-phenylundecane.

PREPARATION OF PHENYLDODECANES

Example 1.—3-phenyldodecane

3-phenyldodecane was prepared by the reduction of 3-phenyl-3-dodecanol. 3-phenyl-3-dodecanol was synthesized in the following manner. The Grignard of ethyl bromide was prepared by reacting ethyl bromide with a suspension of magnesium in boiling anhydrous ether. To 1.5 moles of ethyl magnesium bromide was added 348 gm. of caprophenone over a period of 2½ hours. The mixture was decomposed with a HCl-water mixture and the organic layer removed. The aqueous layer was extracted with ether, the combined ether extracts and organic layer washed with water, and dried. Distillation in vacuo yielded 234 gm. of 3-phenyl-3-dodecanol (contaminated with some 3-phenyldodecene) boiling at 144—146° C./1.5 mm.

A mixture of 195 ml. of glacial acetic acid, 11.7 gm. of red phosphorus, and 4 gm. of iodine were gently warmed in a flask until the iodine is completely dissolved. 4 ml. of water followed by 90 gm. of 3-phenyl-3-dodecanol was added. The mixture was gently boiled under reflux for 5 hours. It was then cooled, filtered, and diluted with 1-liter of water. The organic layer was removed and the aqueous layer extracted repeatedly with ethyl ether. The

2

ether washings and the organic layer were combined and washed successively with 1% sodium bisulfite and dilute sodium carbonate and dried over anhydrous calcium chloride. The ether was removed by distillation and the product distilled in vacuo. The principal cut, 118° C.—119° C./1.1 mm., was then treated as follows: 70 gm. of the product and 130 ml. of absolute ethyl alcohol were treated with 14 gm. of metallic sodium at such a rate as to cause gentle boiling. When all the sodium had reacted the mixture was treated with ice water, acidified with concentrated hydrochloric acid and the organic layer removed. The acid layer was extracted with petroleum ether. The combined extracts and organic layer were washed with water and dried. Vacuum distillation of the product yielded the desired 3-phenyldodecane boiling at 122—123° C./2 mm.

Example 2.—Preparation of 1-phenyldodecane

Lauric acid chloride was reacted with benzene and aluminum chloride to produce n-undecyl phenyl ketone. The latter was reduced with zinc amalgam to produce 1-phenyldodecane.

Example 3.—Preparation of 2-phenyldodecane

The Grignard of decyl bromide was prepared and reacted with acetophenone to give 2-phenyl-2-dodecanol. The latter was reduced by the same method as employed in the preparation of 3-phenyldodecane according to Example 1.

Example 4.—Preparation of 4-phenyldodecane

Pelargonic acid chloride was reacted with benzene in the presence of aluminum chloride to give normal octyl phenyl ketone. The latter was reacted with normal propyl chloride in the Grignard reaction to produce 4-phenyl-4-dodecanol which was reduced to 4-phenyldodecane by the method employed in Example 1.

Example 5.—Preparation of 5-phenyldodecane

n-Heptyl phenyl ketone was prepared by reacting caprylic acid chloride with benzene in the presence of aluminum chloride. The ketone was then reacted with normal butyl chloride in the Grignard reaction. The product 5-phenyl-5-dodecanol was reduced to 5-phenyldodecane by the method of Example 1.

Example 6.—Preparation of 6-phenyldodecane

Caproic acid chloride was reacted with benzene in the presence of aluminum chloride to produce n-amyl phenyl ketone. The latter was reacted with normal hexyl chloride in the Grignard reaction. The product 6-phenyl-6-dodecanol was reduced to 6-phenyldodecane by the method of Example 1.

SULFONATION

Each of the above alkyl aryl hydrocarbons was sulfonated to produce the corresponding sulfonate. The method employed was identical in all instances and will be exemplified by the following sulfonation of 3-phenyldodecane.

About 200 ml. of liquid SO₂ was transferred to a flask containing 20 gm. of 3-phenyldodecane. To this mixture was added 6.5 gm. of stabilized SO₃ (Sulfan B) dissolved in 20 ml. of liquid SO₂. The addition required 10 minutes, stirring vigorously throughout. The SO₂ was allowed to evaporate and the resultant product subjected to vacuum to remove last traces of SO₂. It was then poured into water, filtered, neutralized with caustic to a faint brilliant-yellow end point. On cooling, the sulfonate precipitated from solution and was recrystallized from water. The sulfonate could not be isolated from water in all cases. It was salted out using isopropyl alcohol and Na₂CO₃ in those instances.

3
LAUNDER-OMETER DATA

Each of the above compounds was tested for detergency in (1) distilled water, (2) water of 240 p. p. m. hardness, and (3) water of 720 p. p. m. hardness, respectively. In addition an isomeric compound, namely, the sodium sulfonate of tetrapropyl benzene was also examined for comparison. The latter compound was prepared by reacting benzene with a propylene polymer (tetramer) derived from the polymerization of propylene in the presence of phosphoric acid, followed by sulfonation and neutralization.

Table I shows the result of soil removal tests at various concentrations of each of the compounds.

¹ Concentration—percent active ingredients.

The superiority of the salts of 3-phenyldodecane and 3-phenylundecane are shown more graphically in Figures 1 and 2.

Figure 1 represents Launder-Ometer data according to the Hunter reflectometer measurements of each of the compounds evaluated in 240 p. p. m. hardness water, while Figure 2 shows the evaluation of the same compounds in 720 p. p. m. hardness water. Examination of each figure rapidly reveals the superior detergency of 3-phenylundecane and 3-phenyldodecane sodium sulfonates which is reflected in the curves A and B respectively on each of the drawings. While these compounds are superior in the lower concentrations they lose none of their effectiveness at the higher concentrations, wherein all detergents tend to become equalized.

Although the invention has been described with respect to the sodium sulfonates of the respective alkyl aryl hydrocarbons, it is equally applicable to the other alkali metal salts thereof, namely, potassium, lithium and ammonium sulfonates respectively.

Having described the invention in the manner such that it may be practiced by those skilled in the art, what is claimed is:

1. An aqueous detergent solution consisting essentially of water and .04% of the sodium salt of a monosulfonated benzene to one position of which is attached the third carbon atom of a straight chain alkyl radical containing 11 to 12 carbon atoms.
2. A detergent solution according to claim 1 wherein the sulfonated benzene is 3-phenyldodecane.
3. A detergent solution according to claim 1 wherein the sulfonated benzene is 3-phenylundecane.
4. A detergent solution according to claim 1 wherein the water has a hardness of 240 parts per million.
5. A detergent solution according to claim 2 wherein the water has a hardness of 240 parts per million.
